[57] CLAIM

The ornamental design for a rotating bed for a sunbather, as shown and described.

DESCRIPTION

FIG. 1 is a perspective view of a rotating bed for a sunbather showing our new design;

FIG. 2 is a typical side elevational view thereof, all sides being mirror images of the side shown in FIG. 2;

FIG. 3 is a top plan view thereof; and,

FIG. 4 is a bottom view thereof.
